PER CENT TO URBAN DAVID CLARK, OF TORONTO, ONTARIO, CANADA

MACHINE FOR DELIVERING NEWSPAPERS AND THE LIKE

Application filed February 9, 1928. Serial No. 253,110.

This invention relates to a machine for delivering newspapers and the like as described in the present specification and illustrated in the accompanying drawings which form part 5 of the same.

The invention consists essentially of the novel features pointed out broadly and specifically in the claims for novelty following a description containing an explanation in detail of an acceptable form of the invention.

For the sake of expediency and public convenience, newspapers are now largely sold from open containers or boxes which are placed upon the public highways and left unattended, the vendor depending entirely upon the honour and honesty of the purchasers for his cash returns; it is well known that the returns fall short of the sum represented by the number of newspapers removed from the box, thus resulting in an appreciable pecuniary loss. The newspapers, moreover, are exposed to the elements and on exceptionally rainy days they are often completely soaked and spoiled, to the inconvenience and dis- 25 appointment of both purchaser and vendor.

The objects of the invention, therefore, are to build an efficient machine that will prevent, to a great extent, pecuniary loss to the vendor, and shield the newspapers from dust, 30 rain, snow and sleet; to construct such a device so that it may, if desired, provide space for advertising matter; and generally, to improve upon the machine shown in an application for a patent of the United States of 35 America, filed as Serial No. 192,922.

In the drawings, Figure 1 is a perspective view of the device.

Figure 2 is a perspective view of the frame and operating mechanisms, removed from the casing.

Figure 3 is a bottom plan view of the newspaper platform.

Figure 4 shows a detail of construction.

Figure 5 is an end view of Figure 2 showing parts of the frame broken away.

Figure 6 is a section on line 6—6 in Figure 2.

Figure 7 shows a modification in the construction of the newspaper ejecting means.

Figure 8 is a section on line 8—8 in Figure 1.

Figure 9 is a side elevation of a set of ejecting finger and guide member as shown in Figure 7, showing the guide partly in section.

Like numerals of reference indicate corresponding parts in the various figures.

Referring to the drawings, the newspapers 10 are deposited upon the platform or ele- 60 vator 11 which is suspended within the frame 12 by cables 13 and 13A trained over the corner pulleys 14 and anchored in the pulleys or wheels 15 and 15A, respectively; the wheels 15 and 15A are fixed on the shaft 16 65 which is journaled in the frame 12 and has at one end the ratchet wheel or driving wheel 17 fixed thereto. By depositing newspapers one upon another with their fold all facing one way (as shown in Figure 8), the pile of 70 newspapers is uneven, or in other words, the uppermost newspaper is not parallel with the lowermost one; in order, therefore, to have the uppermost newspaper always lying approximately parallel with the ground, at least 75 when in a position from which it is to be discharged out of the machine, the platform is made to travel upwardly from an initial or lowermost slanted position to a final or uppermost substantially horizontal position, 80 and this is accomplished by making the pulleys 15A to a larger diameter than the pulleys 15 and anchoring the front wires 13A to the pulleys 15A. By turning the shaft 16 to raise the platform, more of the wires 13A 85 will be wound around the pulleys 15A than will be wound of the wires 13 around the pulleys 15, so that the platform will gradually and finally assume a horizontal position when it has reached its uppermost position. 90 Thus, the pulleys 15 and 15A form means of compensating for the uneven thickness of a pile of newspapers.

The ratchet 17 is rotated to wind the cables 13 and 13A around their respective pulleys 95 by the reciprocating action of the ratchet driving arm or member 19. The arm 19 and ratchet 17 are so made that the latter can only be driven by the former in the direction of the arrow (Figure 6). A dog 20 piv- 100

oted at 20A is positioned to engage with the ratchet 17 so as to normally prevent the ratchet from rotating in a direction opposite to that imparted by the arm 19, or in other words, opposite to that indicated by the arrow; a rod 22, sliding in the frame, is pivotally connected at the bottom end to the dog and is urged or pulled in a downwardly direction by the action of a spring 23, the upper end of the rod terminating in a handle 24. The dog can therefore be actuated to disengage or release the ratchet 17 by pulling the rod 22 upwardly by the handle 24.

The driving member 19 is pivoted as at 25 in one of the oscillating arms or levers 26 of the newspaper ejecting mechanism, and pivotally carries, intermediate of its length the rod 27 terminating in the button 28 and sliding in the bearing 29; a spring 30 is fastened at the lower end to the driving member 19 and at the upper end to the frame, and is tensioned to just overcome the combined weight of the rod 27 and driving member 19, so that normally, the action of the tensioned spring is to lift the member 19 off the ratchet 17 and render same ineffective to rotate the ratchet when reciprocating back and forth with the lever 26 from which it derives its reciprocating motion.

An arm 31 is fixed on the horizontally-arranged shaft 32 journalled in the frame and is so positioned on the shaft and sized as to engage or bear upon the button 28 of the rod 27; on the same shaft is fixed a feeler arm 33 positioned preferably at about mid-length of the shaft and extending out to within a short distance of the front of the frame. The function of the feeler arm is to rotate the shaft 32 and raise the arm 31 clear of the button 28 when the platform has risen to a point below the highest possible position from which the uppermost of the newspapers upon the platform can be discharged through the discharge slot or opening 34 made through the front wall of the casing 35. As explained hereinbefore, the tension in the spring 30 is such as to just overcome the combined weight of the rod 27 and ratchet 19, so that as long as the arm 31 bears upon the button 28 (see Figure 5) the additional weight of the arm 31 will overcome the tension of the spring 30 and the ratchet arm 19 will operatively engage with the ratchet 17.

It will be manifest that such a feeler arm 35 is necessary to control or check the rising motion of the platform, since the slot 34 is fixed and the size or thickness of each newspaper issue varies from day to day while the platform always rises by equal increments 40 for every partial turn given to the ratchet 17 by the motion of the arm 26.

The arms 26 of the ejecting mechanism are pivoted in the frame as at 37 and loosely carry at their upper end the transverse shaft 38. The arms 26 are oscillated by connecting

one of said arms to a crank rod 39 which in turn connects with a crank pin 40 carried by the ratchet 41; the ratchet 41 is fixed on the shaft of the coin-controlled operating mechanism—designated by the numeral 42—of which 43 indicates the operating handle. 70

On one end of the shaft 38 is fixed a lever 44; a link 45 is pivotally connected at the upper end to the lever 44 as at 46, and at the lower end to the crank rod 39 as at 47. As the ratchet 41 rotates, the link 44 oscillates about the axis of the shaft 38 and imparts partial oscillatory rotations to the shaft. To the shaft 38 are fixed the castings 48 having the spaced side walls 49 and connecting bottom portion 50, and between the side walls 49 and on the shaft 38 are loosely mounted the newspaper ejecting fingers or members 51 having the sharp ends 52; the fingers are therefore free to swing downwardly around the shaft 38 until they engage the bottom portion 50 in each casting. 75

As the ratchet 41 is rotated, the motion of the crank pin 40 causes the ejecting fingers to rise at their sharp or outer ends as well as to travel rearwardly, and then to lower at their outer ends to engage and bear upon the uppermost newspaper while they travel forwardly; the forward travel of the ejecting fingers slides the newspapers forwardly 80 toward and finally partly through the slot. 90

In order to determine the anti-clockwise or left-hand rotation of the operating crank, suitable means are provided, such as a dog 54 normally engaging the ratchet 41; and similarly, the handle is normally retained in a normal or operative position by means, for instance, of a spring 55 tensioned between one of the levers 26 and the frame, the arms and ejecting fingers being normally in the 100 position shown in Figure 2. 105

The platform is formed substantially as shown, having the plate 56 from which project the extensions 57 to the ends of which the wires 13 and 13A are fastened. Plates 58, secured to the inside of the ends of the frame, form a magazine-like unit or compartment for the newspapers. 110

The plate 56 is perforated as at 58A to form a clearance for the passage of the arm 59 which is freely mounted on the shaft 32. In the path of the arm 59 is the lever 60 pivotally mounted under the platform and sized to engage the arm 61 of the plate 62 which swings to close the coin slot 63 made through 115 the casing. When the last newspaper has been discharged, the arm 59 falls by gravity into the slot 58A, tilts the lever 60 to engage the arm 61 and swing the plate 62 to close the coin slot. 120

The frame is constructed substantially as shown, mounting all the various parts of the mechanism or mechanisms, so that the entire frame and mechanism can be easily placed into the casing and removed as easily. The 130

casing is provided with a hinged lid 65 which can be locked and opened to load the machine with newspapers. The coins inserted into the machine, and particularly into the coin-central operating mechanism, through the coin chute 66, fall out and into a suitable coin receptacle 67. The casing has preferably the shield or cover 68 above the slot 34, and may be provided with suitable cleats 69 for inserting advertising signs or bulletins. The machine is preferably supported above the ground by means of a suitable stand. The frame is deposited into the casing with the members 70 resting upon the floor of the casing, and the frame is secured in position by a number of screws passed through the casing and threaded into registering holes 71 in the frame.

As newspapers sometimes have a tendency not to lie flat one upon another when made or deposited into a pile, a pair of springs 73 are secured to the inside of the lid 65 and formed to extend downwardly so as to be engaged by the uppermost newspaper; such springs exert a pressure upon the uppermost newspaper tending to flatten it down and serving as a means for guiding the newspaper being ejected into the newspaper slot 34.

The ejecting fingers may also be made as shown in Figure 9—designated in this figure as 51A—sliding back and forth upon guide members or straps 75 which are loose on the shaft 32 and therefore engage the uppermost newspaper. When made to slide upon the members 75, the ejecting fingers are loose on the shaft 38 which may also be loose in the arms 26, and the link 45 and lever 44 now eliminated.

The guide members are made to support the fingers with their needle clear of the newspapers but to allow the fingers to lower at their needle end, before reaching the end of the forward stroke of the arms 26 so as to cause the uppermost newspaper to be engaged by the needles and ejected. The guide members are made substantially as shown in Figure 9, grooved longitudinally as at 78 to leave side walls 79 slanting down as at 80 and the bottom wall 81 terminating short as at 82. The fingers have the lateral projections 83 sized to slidably engage the side walls 79 so as to retain the needles out of contact with the guide members, the needles finally engaging the uppermost newspaper when the projections 83 ride down upon the slanting portion 80 of the side walls 79. A shield 84 for the needle is preferably provided on each of the ejecting fingers.

The coin control mechanism may be made to any suitable design, such as that disclosed in a co-pending application filed as Serial No. 230,001, and in that coin control mechanism the finger operating lever—designated as numeral 86 in this specification (numeral 60 in said application Serial No. 230,001)—

is preferably extended back of its pivotal point so as to be operable manually by an authorized person and without the agency of the required number of coins.

Operation: The lid is opened and the ejecting fingers and guide members 75 swung back and the handle 43 also operated to move the shaft 38 rearwardly until the arms 26 have reached their rearwardmost position. The elevator is next allowed to lower by releasing the ratchet dog 20 and the driving member 19 with two fingers of one hand, and simultaneously gently pressing down on the elevator with the other hand. The newspapers are next deposited upon the elevator and the ejecting fingers and guide members 75 swung back into operative position above the uppermost newspaper. The handle 43 of the coin control mechanism is then operated to raise the elevator until the uppermost newspaper engages the feeler arm 33, the lever 86 of the coin control mechanism being pressed to allow the mechanism to operate without the agency of the required number of coins. The device is now ready to be operated to vend newspapers.

As the handle 43 is given one turn, the gear 41 causes the levers 26 to oscillate rearwardly and then forwardly, the ejecting fingers moving rearwardly without engaging the newspaper, but finally engaging said newspaper when nearing the end of the forward stroke of the levers 26, said newspaper being slid into the slot 34. The tensioned spring 55 normally retains the handle 43 in operative position, thus serving the function of the spring 53A shown in said co-pending application Serial No. 230,001. As the levers 26 oscillate, the driving member 19 rotates the ratchet 17 on their rearward stroke, winding the cables 13 and 13A to elevate the platform 11. If the action of the ratchet 17 elevates the platform by increments smaller than the thickness of each newspaper being ejected, the feeler arm operates to disengage the driving arm 19 from the ratchet 17. When the last newspaper upon the elevator has been ejected, the arm 59 falls down into the slot 58A of the elevator 11 to cause the plate 62 to close the coin slot 63.

What I claim is:

1. In a machine for delivering newspapers and the like, a casing having a newspaper slot, an elevator for the newspapers movable vertically, pulleys mounted above said elevator, a shaft rotatably mounted under said elevator and having pulleys and a drive wheel rigid thereon, cables trained over said first-mentioned pulleys and secured at one end to said elevator and anchored at the other end in the pulleys on said shaft, ejecting means operating to successively deliver the newspapers into said slot, means actuated by said ejecting means operating to rotate said drive wheel in a direction to raise said

elevator, and means operating to releasably lock said drive wheel as said elevator is gradually raised.

2. In a machine for delivering newspapers and the like, a casing having a newspaper slot, ejecting means operating to successively deliver the newspapers into said slot, an elevator for the newspapers movable vertically to successively feed the newspapers onto said ejecting means, pulleys mounted above said elevator, a shaft rotatably mounted under said elevator and having a drive wheel rigid thereon, a pair of pulleys rigid on said shaft adjacent each end thereof, said pulleys in each pair being made to unequal diameters, front and rear cables in pairs trained over said first-mentioned pulleys and secured at one end to the front and rear of said elevator, respectively, and anchored at the other end in the larger and smaller pulleys, respectively, means operating to rotate said drive wheel to wind said cables around said pulleys on said shaft, and means operating to releasably lock said drive wheel against rotation unwinding said cables.

3. In a machine for delivering newspapers and the like, a casing having a newspaper slot, an elevator for the newspapers free to move vertically, pulleys mounted above said elevator, a shaft rotatably mounted under said elevator and having a drive wheel rigid thereon, a pair of pulleys rigid on said shaft adjacent each end thereof, said pulleys in each pair being made to unequal diameters, front and rear cables in pairs trained over said first-mentioned pulleys and secured at one end to the front and rear of said elevator, respectively; and anchored at the other end in the larger and smaller pulleys, respectively, ejecting means mounted to move from and toward said slot operating to successively engage the newspapers so as to eject same, means actuated by said ejecting means operating to rotate said drive wheel to wind said cables around the pulleys on said shaft, and means operating to releasably lock said drive wheel against rotation unwinding said pulleys.

4. In a machine for delivering newspapers and the like, a casing having a newspaper slot, an elevator for the newspapers movable vertically, pulleys mounted above said elevator, a shaft rotatably mounted under said elevator and having pulleys and a ratchet wheel rigid thereon, cables trained over said first-mentioned pulleys and secured at one end to said elevator and anchored at the other end in the pulleys on said shaft, ejecting means operating to successively slide the newspapers into said slot, a driving member actuated by said ejecting means operating to rotate said ratchet wheel in a direction to raise said elevator, means operating to releasably lock said ratchet wheel as said elevator is gradually raised, an upwardly extending rod pivotally connected to said driv-

ing member and supported thereby, a tensioned spring operating to normally raise said driving member out of operative engagement with said ratchet wheel, a hinged arm engaging at the free end thereof with said upwardly extending rod and overcoming the tension in said spring, and a hinged feeler movable with said hinged arm and extending in the path of the rising newspapers operating to swing said hinged arm upwardly when the uppermost of said newspapers reaches a pre-determined position relative to said slot.

5. In a machine for delivering newspapers and the like, a casing having a newspaper slot, an elevator for the newspapers operating to successively bring the newspapers into discharging position, a hinged member oscillating rearwardly from and forwardly toward said slot, and ejecting means hinged at one end to said oscillating member operating to engage the uppermost newspaper on the forward stroke so as to eject same and to clear said newspaper on the rearward stroke.

6. In a machine for delivering newspapers and the like, a casing having a newspaper slot, an elevator for the newspapers operating to successively bring the newspapers into discharging position, a hinged member oscillating rearwardly from and forwardly toward said slot, straps pivotally mounted above said elevator to engage the uppermost of said newspapers, and ejecting fingers pivotally mounted at one end to said oscillating member and sliding upon said straps, said straps operating to allow said fingers to lower and engage said uppermost newspaper on the forward stroke of said oscillating member.

7. In a machine for delivering newspapers and the like, a casing having a newspaper slot, an elevator for the newspapers operating to successively raise the newspapers into discharging position, a member hinged to oscillate between a rearward and a forward position, a tensioned spring mounted to normally retain said member in its forward position, handle-operated means operating to oscillate said member rearwardly and forwardly, straps pivotally mounted above said elevator and engaging the uppermost of said newspapers, and ejecting fingers hinged to said member and slidably engaging said straps, said straps operating to allow said fingers to lower and engage said uppermost newspaper on the forward stroke of said member.

Signed at the city of Toronto, this 8th day of November, 1927.

VERNON ALBERT SCOTT. 125
